US00D643165S

(12) **United States Design Patent**
Song et al.

(10) **Patent No.:** US D643,165 S
(45) **Date of Patent:** ** Aug. 9, 2011

(54) **CLOTHES DRYER**

(75) Inventors: **Seung Hyun Song**, Seoul (KR); **Ki Hyuk Kim**, Incheon (KR); **Eun Young Jee**, Seoul (KR); **Min Jung You**, Seoul (KR)

(73) Assignee: **LG Electronics Inc.**, Seoul (KR)

(**) Term: **14 Years**

(21) Appl. No.: **29/364,070**

(22) Filed: **Jun. 18, 2010**

(30) **Foreign Application Priority Data**

Dec. 22, 2009 (KR) 30-2009-0056236

(51) **LOC (9) Cl.** **15-05**

(52) **U.S. Cl.** **D32/8**

(57) **CLAIM**

The ornamental design for a clothes dryer, as shown and described.

DESCRIPTION

FIG. 1 is a top, front, perspective view of a clothes dryer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing portions of a clothes dryer are included for the purpose of illustrating environmental structure and form no part of the claimed design.
